BOMB FUZE LINER CENTERING CLAMP
 Cary F. Milliner, Jr., Onley, Va., assignor to the United States of America as represented by the Secretary of the Navy

Filed Oct. 10, 1958, Ser. No. 766,626

3 Claims. (Cl. 102—70)

(Granted under Title 35, U.S. Code (1952), sec. 266)

The invention described herein may be manufactured and used by or for the Government of the United States of America for governmental purposes without the payment of any royalties thereon or therefor.

This invention relates to a centering tool to be used in centering a bomb fuse liner.

During the bomb loading operation the charging tube is subjected to a torque which frequently deforms the tube to the extent that it must be replaced. This is both a financial and time loss which can be avoided. Patent application of Frank C. Pars, Serial No. 715,163, filed February 13, 1958, and now Patent Number 2,981,189, shows a complementary tool serving to avoid this damage to the charging tube.

An object of the present invention is to provide a centering clamp for a bomb fuse liner which will hold the fuse liner centered and decrease the torque to which the charging tube is subjected.

A further object is to provide a fuse liner centering clamp to prevent the application of torque to the rear charging tube of a low drag bomb when the fuse liner is assembled to the charging tube and to maintain the fuse liner centered during the loading operation.

A still further object is to provide a ring formed from a pair of hinged semi-circular sections one of which carries a clamp to engage a fuse liner, the ring having spaced legs adapted to engage the bomb body.

It is a still further object of the present invention to provide a physical connection between the bomb body and the fuse liner to prevent relative motion between said fuse liner and the bomb body during the loading operation.

Other objects and many of the attendant advantages of this invention will be readily appreciated as the same becomes better understood by reference to the following detailed description when considered in connection with the accompanying drawing wherein:

FIG. 1 is a top elevation;

FIG. 2 is a section on line 2—2 of FIG. 1; and

FIG. 3 is a section on line 3—3 of FIG. 1.

Referring to the drawings in which like numbers denote like parts in the several views, there is shown a bomb body 8 on which the centering clamp 10 is mounted.

The centering clamp 10 comprises a pair of semi-circular rings of different diameters. The smaller half ring 12 is hinged to the larger half ring 14 by pins 16. Legs are spaced 120° apart, two of the legs 18 being attached to the smaller half-ring while the third leg 20 is centrally secured to the larger half-ring. The legs 18 have inturned ends 22 for engagement with the rim 24 of a bomb body 8. The other leg 20 is bent to form a shoulder 26 for engagement with the rim 24 and is extended to form an extended finger grip 28 used in locking clamp in position or for releasing the clamp after use.

A fuse liner 30 carried within the bomb body has a charging tube (not shown) attached to it by the nut 32. The charging tube is attached by threading the charging tube fitting nut onto the charging tube fitting, the torque applied is resisted through the dowel pins between the

2

fitting and the fuze liner. The clamp being secured to the fuze liner resists any torque applied through the dowel pins to the fuze liner. Without the use of this clamp, the possibility exists that in threading the charging tube fitting nut assembly onto the charging tube fitting, excessive torque will be transmitted which may twist or distort the charging tube. As the charging tube is surrounded by live explosive this is highly undesirable.

The smaller half-ring 12 of the centering clamp 10 has a bridge 34 secured at the centerpoint and above the half-ring. This bridge was a wing screw 36 and a key 38, both projecting toward the half-ring, the key to engage a slot 40 cut into the rim 42 of the fuze liner 30, and the wing screw to be turned to clamp securely the rim 42 between it and the half ring 12.

The centering clamp is secured to the fuze liner by clamping the rim 42 between the smaller half-ring and the wing screw 36. Key 38 helps prevent relative rotary motion between the clamp and fuze liner. The legs 18 are caught on the rim 24 of the bomb body and the leg 20 snapped into place over the same rim. The fuze liner is now centered relative to the bomb body and the charging tube. The clamp prevents displacement of the fuze liner and attached charging tube from normal center line position during the loading operation. This also facilitates the assembly of the base plate to the bomb body after the loading is complete.

Obviously many modifications and variations of the present invention are possible in the light of the above teachings. It is therefore to be understood that within the scope of the appended claims the invention may be practiced otherwise than as specifically described.

What is claimed as new and desired to be secured by Letters Patent of the United States is:

1. In combination, a bomb, a central bomb fuze liner for said bomb and a clamp for centering a bomb fuze liner within said bomb during an explosive loading operation thereof, said clamp comprising a pair of half-rings hinged together to form a ring when in fuze liner supporting position, an outer rim formed on said bomb, means attached to said half-rings and engaging said rim to support and center said fuze liner supporting ring with relation to the bomb, and means carried by one of said half-rings supporting the fuze liner within the ring.

2. A clamp for centering a fuze liner within a bomb during explosive loading operation according to claim 1 wherein the fuze liner supporting ring centering means comprises three legs spaced 120° apart around the ring.

3. The combination of a tubular fuze liner for a bomb with a centering clamp for centering the fuze liner within a bomb during explosive loading operation, the bomb being formed on its exterior wall with an annular rim, said centering clamp comprising a hinged pair of half-rings forming a ring when in fuze liner supporting position, said ring being secured to said fuze liner, and means attached to said ring and engaging the bomb wall on the rim to center and support the ring and fuze liner within the bomb.
